UNITED STATES PATENT OFFICE.

CORNELIUS COOK, OF FREMONT, NEBRASKA.

GRADER AND DITCHER.

SPECIFICATION forming part of Letters Patent No. 357,522, dated February 8, 1887.

Application filed May 24, 1886. Serial No. 203,169. (No model.)

To all whom it may concern:

Be it known that I, CORNELIUS COOK, a citizen of the United States, residing at Fremont, in the county of Dodge and State of Nebraska, have invented certain new and useful Improvements in Graders and Ditchers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a plan view. Fig. 2 is a vertical longitudinal section on line $x\ x$, Fig. 1. Fig. 3 is a transverse section on line $y\ y$, Fig. 1. Fig. 4 is a similar section on line $z\ z$, Fig. 1; and Fig. 5 is a detail view 20 of the cutting-wheel.

My invention relates to graders and ditchers; and it consists in the construction and novel combination of parts, as hereinafter described, and pointed out in the claims.

Referring by letter to the accompanying drawings, A designates the main frame, which is rectangular in form, and is provided in its side rails, B, with mortises M, made vertically through it to receive the perforated standards M', to the lower ends of which the sled-runners M² are secured and provided with proper metallic soles. Bolts M³ are passed laterally through the mortises in the side rails, B B', and through any of the desired perforations P in the vertical standards M', to give the main frame the proper or desired elevation above the runners, so that but a small portion of the cutting-cylinder C will be in operation when a shallow ditch is to be made.

The cutting-cylinder C is mounted on the main or driving shaft C', and is provided with a wide peripheral or rim flange, C², which extends rearwardly from the vertical front face of the cutting-cylinder, and is provided on its inner face or periphery with buckets or lifters C⁴, which carry the loosened dirt up and deposit it upon a stationary inclined sheet-metal apron or chute, D, which latter directs the dirt to and delivers it upon the endless carrier E.

The cutting-cylinder C has two diametrically-opposed radial slots, S S', in its vertical face, each of which is provided with a cutter

or blade, S², which project slightly in advance of one edge of the slot in which it is located. The rim-flange C² of the cutting-cylinder C is 55 provided with a slot, S³, through which a blade, S⁴, riveted to said flange, projects, and these several knives serve to loosen the dirt as the machine is propelled along the line of the ditch. 60

The lower half of the cutting-cylinder C is closed by a stationary semicircular sheet, F, of metal, which is secured by arms F' to the side rails, B, of the main frame and prevents the dirt from falling from the buckets or lifters C³ as it is being carried up to be deposited on the inclined chute D. This metal chute D is secured to the upper edge of an inclined metal sheet, G, the lower edge of which sheet G is secured to the upper edge of the stationary 70 semicircular sheet F, said sheet G extending inwardly nearly to the vertical front face of the cutting-cylinder C.

An auxiliary frame, H, has the inner ends of its arms secured in a recess, H', in the upper 75 face of the side rail, B, and is provided at its outer end with a roller, H², over which the outer portion of the endless carrier E runs, the inner portion of said endless carrier E running over a pulley, I, secured to the front end 80 of the horizontal shaft I', rotating in bearings I² I³ at the lower ends of the inclined arms I¹ I³, secured in the inner face of the side rail, B', of the main frame. The shaft of the pulley H² is provided on its rear end with a sprocket-wheel, K, and this sprocket-wheel K is connected by a sprocket-chain, K', to a sprocket-wheel, K², on the driving-shaft C. The driving-shaft C is provided with a sprocket cone-pulley, K³, immediately in rear of the sprocket-wheel K², and this sprocket cone-pulley K³ is connected by a sprocket-chain, L, with a sprocket cone wheel or pulley, L', on the rear end of a shaft, M⁴, having bearings in boxes M⁵ M⁶, secured upon the upper face of the side 90 rail, B'. At its front end the shaft M⁴ is provided with a miter gear or pinion, N, which pinion N engages a miter gear or pinion, P', on the end of a transverse shaft, Q, working in bearings in boxes Q', and having at its inner 100 end the drum or windlass R, upon which the draft-chain R', provided with the grappling-hook R², is wound as the machine is propelled forward.

The machine is propelled by two vertical steam-engines, *a a*, which drive a worm, *b*, the latter being connected with a worm-wheel, *c*, on the driving-shaft *C'*.

5 *k* designates the steam-boiler, *l* the fuel-box, and *m* the water-tank, which are located on the platform of the main frame.

The plow *x*, in front of the journal of the cutting-cylinder *C*, is to open a way for the 10 box *Y*, in which the front end of the shaft *C'* is journaled.

The machine is to be adjusted to cut a ditch of the desired depth, and ordinarily its limit is five feet depth.

15 Near the rear end of the main frame, just inside of the rear cross-timber, I provide a downwardly-curved guard, *X*, of the same arc as the cutting-cylinder, the object of which is to prevent the runners from dropping into the 20 ditch, the said guard *X* running in the ditch for this purpose.

Having described this invention, what I claim, and desire to secure by Letters Patent, is—

25 1. The combination, with the main frame mounted on vertically-adjustable runners, and provided with the cutting-cylinder on the main driving-shaft provided with a worm-wheel and the cone sprocket-wheels, of the 30 metal apron within the cutting-cylinder, the horizontal shaft with sprocket-gears and a miter-gear, the transverse shaft with miter-gear and drum, the chain with claw-hooks, the endless apron and the sprocket-chains connecting the endless-apron shaft with the 35

sprocket-wheels on the horizontal shafts, and the worm-wheel connected to the engines, substantially as specified.

2. The combination, with the main frame provided with the cutting-cylinder, and mechanism, substantially as described, for operating it, of the vertically-adjustable runners connected to the perforated standards working in mortises in the main frame and secured in place by adjusting-bolts, substantially as 45 specified.

3. The combination, with the main frame mounted on adjustable runners, of the cutting-cylinder mounted on the driving-shaft and provided with the radial and peripheral 50 knives, the metal apron and guard, and the endless carrier, substantially as specified.

4. The combination, with the main frame, and the shaft of the cutting-cylinder supported in bearings on the main frame, of the 55 opening-plow secured in front of and over the front bearing of the main shaft, substantially as specified.

5. The combination, with the main frame and cutting-cylinder, and mechanism, substantially as described, for operating said cutting-cylinder, of the rear guard having its arc corresponding with the lower arc of the cutting-cylinder, substantially as specified.

In testimony whereof I affix my signature in 65 presence of two witnesses.

CORNELIUS COOK.
